DRAFTING PENWIPER

Filed Feb. 3, 1931

UNITED STATES PATENT OFFICE

JAMES R. PARRISH, OF NASHVILLE, TENNESSEE

DRAFTING PENWIPER

Application filed February 3, 1931. Serial No. 513,198.

The present invention relates to drafting pen wipers and has for an important object thereof the provision of a pen wiper and support therefor which may be disposed at a 5 point convenient to the draftsman or the like for use in cleaning drafting pens.

Another object of this invention is to provide a wiper of this kind which is so constructed as to thoroughly and simultaneously 10 cleanse each blade of a drafting pen in one operation.

A further object of this invention is to provide a device of this kind which is so constructed as to permit the replacement of the 15 pen wiping element or the rotation or movement of the pen wiping element upon the frame so as to present a clean wiper to the pen blades.

A still further object of this invention is 20 to provide a device of this kind which is very light in weight and which may be conveniently disposed on a drafting table or board or, if desired, hung on a nail or hook closely adjacent to the drafting board.

The above and various other objects and 25 advantages of this invention will in part be described in and in part be understood from the following detailed description of the present preferred embodiment, the same being illustrated in the accompanying drawings, wherein:—

Figure 1 is a detail front elevation of the device having the pen wiping element mounted on the supporting frame;

Figure 2 is a similar view in side elevation;

Figure 3 is a side elevation of the frame having the pen wiping element removed therefrom;

Figure 4 is a detail front elevation of the 40 bare frame;

Figure 5 is a side elevation of the same;

Figure 6 is a detail side elevation of the upper supporting element;

Figure 7 is a top plan view of the upper 45 pen wiper supporting element;

Figure 8 is a detail front elevation of the same;

Figure 9 is a detail side elevation of this 50 device showing the manner of wiping the pen by means of this device;

Figure 10 is a detail front elevation of a modification of the frame without the pen wiping element mounted thereon;

Figure 11 is a detail side elevation of the 55 modified form of this invention;

Figure 12 is a detail rear elevation of the modified form;

Figure 13 is a detail front elevation of the 60 modified form having the pen wiping element mounted thereon, and

Figure 14 is a detail side elevation of the modified form having the pen wiping element mounted thereon.

Referring to the drawings wherein like numerals of reference designate corresponding parts throughout the several views, the letter F designates generally a supporting frame for a pen wiping element, this pen wiping element being designated as 6 and composed of an endless strip of cloth or other pliable material which is removably mounted on the frame F. The frame F as disclosed in Figures 1 to 5, inclusive, and Figure 9 comprises a pair of upwardly converging leg members 1 and 2 which terminate in an eye 3 or loop 3, the purpose for which will be hereinafter described.

An upper pen wiper supporting element generally designated as 9 which comprises a plate having a looped rear end portion 4 and a flanged forward edge 5 is adapted to be positioned on the frame F intermediate the eye 3 and the converging ends of the legs 1 and 2, the securing loop 4 of the member 9 being disposed about the portion 12 of the leg 1 and the portion 13 of the leg 2, these portions 12 and 13 being disposed in parallel relation to each other and, if desired, soldered or welded together so as to form a relatively rigid structure.

The loop 4 may be secured to the intermediate portions 12 and 13 of the leg members 1 and 2, respectively, in any desired manner as by soldering, welding or the like, so as to prevent vertical movement of the upper pen wiper supporting element 9 on the frame F. The leg member 1 at the lower end thereof is preferably bent upwardly, as at 10, and this upwardly bent portion 10 continued forwardly in a horizontal extension 11 which is offset up-

wardly from the lower end of the leg member 1 and the extension 11 terminates in a downwardly extending portion 7, the end of which is adapted to engage a table or the like so as to cooperate with the lower end 10 in supporting the leg member 1 in substantially vertical position. In like manner, the leg 2 of the frame F is provided with a similarly offset portion 11' which at the forward end thereof terminates in a depending leg 8 which leg 8 cooperates with the leg members 1, 2 and 7 in supporting the frame F in upright position. These extensions 11 and 11' of the leg members 1 and 2, respectively, constitute lower pen wiper supporting elements which cooperate with the upper pen wiper supporting element 9 in supporting the wiper 6 on the frame F. Preferably, the leg members 1 and 2 are inclined forwardly a slight degree so as to provide a stable support or frame which will be maintained in upright position at all times. This upper pen wiper supporting element 9 is preferably constructed of relatively thin metal so that when the pen 14 is pushed downwardly over the top of this member 9, the blades of the pen 14 will press the wiper 6 inwardly and tension the leg members 1 and 2. As the pen 14 is moved further down on the wiper 6, the wiper will be placed under increased tension and the natural tendency will be to thoroughly clean the inner surfaces of the two blades of the pen 14.

The frame F may be constructed of a single piece of wire or the like which has inherent resiliency so that when the pen 14, as disclosed in Figure 9, is moved downwardly over the wiper 6 and the upper supporting member 9, the leg members 1 and 2 will be forced inwardly on account of the increased pressure applied on the wiper 6. As disclosed in Figures 10 to 14 inclusive, the frame F' comprises a single vertically disposed leg 1' which at the upper end thereof is provided with an eye or loop 3' and which has secured adjacent the upper end thereof and below the eye 3' an upper wiper supporting member 9'.

This supporting member 9' has a loop 4' at the rear end thereof which engages about the vertically disposed leg 1' and an upwardly extending lug 5' is secured to the supporting member 9' at the forward end thereof so as to retain the wiper 6' on the supporting member 9' against lateral movement. The leg member 1' is provided with an offset portion 15 intermediate the upper and lower ends thereof so as to increase the resiliency of the leg member 1'. The lower end of the leg member 1' is bent horizontally, as at 21, this horizontal extension 21 being bent upwardly, as at 20, so as to provide a lower wiper supporting element 19. The wiper supporting element 19 is bent downwardly, as at 16, and continued in a horizontal direction, the horizontal extension 17 at the opposite end thereof being bent upwardly, as at 18, and rearwardly, as at 22,

so as to provide a second lower wiper supporting element 22, the end of the wiper supporting element 22 being bent downwardly, as at 23, so as to provide a leg member which cooperates with the horizontal portions 17 and 21 in supporting the leg member 1' in substantially vertically disposed position. This member 1' is preferably inclined forwardly a slight degree so as to stabilize the structure in a manner similar to the frame member F shown in Figures 1 to 5 and Figure 9. The pen wiper element 6' is removably mounted on the frame F' engaging the upper supporting member 9' rearwardly of the upstanding lug 5' and engaging the bottom of the frame F' within the offset portions 19 and 22.

When it is desired to remove the wiper 6' from the frame F', the upper end 3' may be pressed forwardly with the horizontal portions 17 and 21 resting on a flat structure so as to tension the leg 1' and loosen the wiper 6' on the frame F'. This same procedure may be followed when it is desired to merely move the wiper 6' about the supporting members 9' and 19 and 22, so as to maintain a clean wiping element adjacent the upper end of the frame F' for engagement by the pen.

It is obvious from the foregoing, that the device herein disclosed may be constructed in varied forms without departing from the spirit of the invention, and while I have disclosed herein two forms of this invention, I do not wish to be limited to the forms herein disclosed.

In the use of this device, the frames F and F' may be disposed on a flat table structure or drawing board, being held in vertically disposed or upright position by means of the supporting legs or, if desired, the frames F and F' may be mounted on a nail or hook disposed in a location convenient to the draftsman. The pen 14 is moved downwardly from the upper end of the supporting members 9 and 9', the wipers 6 and 6' being engaged between the blades of the pen 14 so that as the pen 14 is moved downwardly within the frames F or F', the wiping elements 6 or 6' will be pinched together by the blades of the pen 14, the frames F and F' being so constructed as to constantly urge the upwardly converging sides of the wiper 6 and 6' outwardly so that as the pen 14 is moved downwardly, the wipers 6 and 6' are placed under increased tension.

As disclosed in the drawings, the wipers 6 and 6' are mounted on the frames F and F' in substantially triangular relation, the sides of the triangle being used to wipe the inner surfaces of the blades of the pen, while the base of the triangle is disposed at the bottom of the frames F and F'.

It will be obvious from the foregoing that a relatively simple and at the same time practical pen wiper has been disclosed, which is

so constructed that the pen wiping element may be readily moved about the frame or replaced by a clean wiper without the use of any instruments or without taking apart any portion of the frame.

It is, of course, understood that various changes and modifications may be made in the details of construction and design of the above specifically described embodiment of this invention without departing from the spirit thereof, such changes and modifications being restricted only by the scope of the following claims.

I claim:

15. 1. A pen wiper of the character described comprising an endless pen wiping element, a frame, and supporting means carried by the frame and engaging the pen wiping element for holding the element in taut condition said supporting means including a vertical member, a pair of lower wiping element supporting members offset from said vertical member, and an upper wiping element supporting member offset from said vertical member, and an upper wiping element supporting member.

20 2. A pen wiper of the character described comprising a pen wiping element, a frame, and upper and lower supporting members carried by the frame and offset forwardly therefrom whereby to hold the pen wiping element in offset relation to the frame.

25 3. A pen wiper of the character described comprising an endless pen wiping element, a supporting frame, said frame having a pair of downwardly diverging leg members, an upper pen wiper engaging element carried by the frame, and means carried by each of the leg members and adapted for engagement with the pen wiping element whereby to tension the pen wiping element on the frame.

40 4. A pen wiper of the character described comprising an endless pen wiping element and a supporting frame therefor, said frame comprising a vertically disposed resilient member, and means carried by each end of said member and adapted for engagement with said element whereby to tension said element on the frame.

In testimony whereof I hereunto affix my signature.

JAMES R. PARRISH.
